(57) CLAIM

The ornamental design for a wall mounted liquid dispenser, as shown.

DESCRIPTION

The claimed wall mounted liquid dispenser is used to store liquid with a button for dispensing the liquid.

FIG. 1 is a view of a wall mounted liquid dispenser showing my new design;

FIG. 2 is a front perspective view thereof;

FIG. 3 is a side perspective view thereof;

FIG. 4 is a top perspective view thereof; and,

FIG. 5 is a bottom perspective view thereof.
